UNITED STATES PATENT OFFICE.

EDWARD WOLFGANG SCHLOEMER, OF MILWAUKEE, WISCONSIN.

COMPRESSED-AIR MOTOR.

SPECIFICATION forming part of Letters Patent No. 748,660, dated January 5, 1904.

Application filed March 30, 1901. Serial No. 53,662. (No model.)

To all whom it may concern:

Be it known that I, EDWARD WOLFGANG SCHLOEMER, a citizen of the United States, residing at Milwaukee, in the county of Milwaukee and State of Wisconsin, have invented a new and useful Compressed-Air Motor, of which the following is a specification.

This invention relates to improvements in compressed-air motors; and it contemplates the expanding of air compressed by a suitable compressor, so as to operate said compressor and also the motor; and the object is to provide an apparatus comprising a motor, a compressor, and expanding means for the air so connected and arranged as to utilize the compressed air in the manner above specified.

With the above object in view the invention consists in the novel features of construction hereinafter fully described, particularly pointed out in the claim, and clearly illustrated by the accompanying drawings, in which—

Figure 1 is a front elevation of my improved motor. Fig. 2 is an end view of the same. Fig. 3 is an enlarged longitudinal section taken through the cylinders. Fig. 4 is a detail section on the line 4 4 of Fig. 3. Fig. 5 is a detail cross-section on the line 5 5 of Fig. 4, and Fig. 6 is an enlarged section taken 30 through the compression-cylinder.

While I have herein shown an apparatus by means of which my invention may be carried into effect, yet I do not limit myself to the construction herein shown, as the same might be varied in many ways without departing from the spirit and scope of my invention.

Referring now more particularly to the accompanying drawings, A designates a suitable stand supporting at its upper end motor-cylinders B and compressor-cylinder C, which latter is preferably disposed between the two motor-cylinders. The compressor-cylinder C is in the present instance one-fourth the diameter of the motor-cylinders. Each of the three cylinders is provided with a piston B', provided with suitable packing and having a piston-rod E, which is movable through a suit-

able stuffing-box F at the lower end of each cylinder. Said piston-rods are connected to 50 a crank-shaft G, which is mounted in the base.

Each of the motor-cylinders is provided with an inlet-port H, which communicates with passages I, leading to the upper and lower ends of the cylinders, each of said passages being provided with a rotary valve J, which is formed tapered and is provided with a spring K, which tends to force it inwardly and exerts enough pressure to make the same fit snugly to its seat. The valve-stems of 60 valves J are connected by crank-arms L L and pitmen P P with eccentrics M on the shaft G. The arrangement is such that when one of said inlet-valves is opened the other is closed, so as to shut off the entrance of air 65 to one side of the piston while the air is entering upon the other side thereof. Each of the motor-cylinders is also provided with two exhaust-valves N, controlling passages leading from the upper and lower ends of the cylinder to a common exhaust-port, said valves being operated in the same manner as the valves controlling the inlet of air—namely, by crank-arms L' L', pitmen P' P', operated by eccentrics Q Q upon said shaft G. 75

The compressor-cylinder is provided with an inlet R, controlled by an inwardly-opening valve S, and with an outlet T at the same end of the cylinder controlled by an outwardly-opening valve U. The outlet T of 80 the compressor-cylinder is connected by pipe D' with a tank T², which tank is connected by a branched pipe 3, extending from its upper end and connected with inlet-ports of each of the motor-cylinders. The tank is 85 also connected with an outlet V at the upper end of the compressor-cylinder similar to the outlet T at the lower end thereof, and said upper end of the cylinder is also provided with an inlet W, similar to the inlet R. Both 90 inlet W and outlet V are controlled by valves X, the valve of the inlet opening inwardly and the valve of the outlet outwardly.

The tank is provided with any heating means, as Y, for heating the air compressed 95 therein. Any means may be used for accom-

plishing this heating of the air, and the tank may be of any construction, protected by a water-jacket, a coating of asbestos, or constructed in any other manner to protect it 5 from the flame of the heater.

The cylinders B are heated by burners Z, positioned at the ends of the cylinders.

The operation of my invention is as follows: Air is compressed in the tank by hand 10 to a pressure of, say, twenty-five pounds and heat applied to the tank. This heat expands the compressed air to from four to six times its original pressure. This expanded compressed air is conducted to the cylinders of 15 the motor operating the pistons thereof and communicating motion to the driving-shaft. This driving-shaft operates the piston of the compressor, which continues the operation of compressing air in the tank. The air in the 20 tank itself is heated by the heating apparatus and used in the cylinders of the motor. The cylinder of the compressor being one-fourth in the present instance of the cylinders of the motor will only compress one-fourth 25 of the amount of air used in said motor-cylinders. This compressed air when heated, however, furnishes more than enough power to operate the motor, so that by the heating there is a gain of three-fourths of the power 30 of the motor, said air being regulated to keep a certain pressure.

As before stated, I do not limit my invention to the particular apparatus herein shown and described, as it may be carried into effect by various forms of motors and 35 compressors; but what I do claim is the arrange-

ment of the parts so as to accomplish the result set forth.

It will of course be understood that air, gas, or any mixture of air and gas may be employed 40 for running this motor.

Having thus fully described my invention, what I claim as new, and desire to secure by Letters Patent of the United States, is—

A motor comprising two motor-cylinders, 45 pistons therein, each motor-cylinder having two parallel, longitudinal passage-ways opening into the cylinder on each side of the piston, rotary valves in said passage-ways adjacent each end thereof, a compressor-cylinder 50 of less diameter than the motor-cylinders and arranged between them, a reservoir-tank, a piston in the compressor-cylinder, pipes leading from each end of the compressor-cylinder to the tank, and thence discharging into one 55 of the longitudinal passages of each motor-cylinder, an exhaust-pipe leading from the other passage, a cranked shaft, piston-rods connected at one end to the pistons, and at their opposite ends to the shaft, two eccen- 60 tries arranged on the shaft adjacent each motor-cylinder, eccentric-rods extending parallel with each motor-cylinder, oppositely-arranged valve-stems, connected at one end to the valves in one of the passages and at their 65 opposite ends to one of said valve-rods, means for initially compressing the air in the tank and means for heating the motor-cylinders.

EDWARD WOLFGANG SCHLOEMER.
